UNITED STATES PATENT OFFICE

NILS ANDOR JACOBSEN, OF HOKKSUND, NORWAY

PAPER MACHINE IN ORDER TO PREVENT BREAKAGE OF THE PAPER ON THE COUCH PRESS OR WIRE CLOTH

Application filed January 3, 1930, Serial No. 418,326, and in Norway January 25, 1929.

On the couch-part of a paper machine it happens that the paper attaches to the wire cloth at some point, so as to be carried with the wire cloth towards the lower couch cylinder. In this manner the paper is caused to be torn along one or more lines forming an acute angle between them or between the line and the edge of the paper, and after a certain interval the paper will be torn from edge to edge so as to be completely broken.

The present invention has for its object to prevent the breakage or interruption of the continuous web of paper in these cases, and this is obtained in accordance with the invention by providing means for dividing the continuous web of paper in two parallel strips by means of a jet of water, said means being actuated automatically as soon as tearing of the paper commences.

By dividing the continuous web of paper in this manner, the extension of the fissure directly across the paper web is prevented, and by gradually moving the jet towards the edge which has been torn, the normal condition with full width of paper is re-established.

The jet may preferably be located approximately midway between the edges of the paper web, but obviously it may also be placed near one of the edges in case it is proved that the paper has a tendency to break in a certain place, for instance owing to a defect in the wire cloth or the like.

Also, if so desired, two or more jets may be provided, and said jets may be adapted to be operated simultaneously or selectively.

The automatic actuation of the jet is obtained in accordance with the invention by conducting the part of the paper web, which is torn off by the wire cloth so as to be carried along with the same, on to a plate or receptacle which is connected in a suitable manner with means actuating the jet as soon as the weight thereof is increased owing to the paper accumulated on the same.

One form of the invention is illustrated on the drawing in a purely diagrammatic manner.

Fig. 1 illustrates the device with all parts in normal position, and Fig. 2 the same de-

vice after the actuation of the jet by means of the automatic device.

1 is the upper and 2 the lower couch cylinder. 3 is the wire cloth and 4 the felt on which the paper 5 is to be carried from the lower couch cylinder.

In case a part of the paper web is carried along with the wire round the lower couch cylinder, it is removed from the wire cloth by means of auxiliary cylinder 6, so as to drop on to the hinged plate 7. This plate is connected for instance by means of a flexible wire or the like with a cock or valve 9 in the water pipe 10 leading to a jet 11 located over the paper web on the wire cloth 3, at a point approximately midway between the edges of the paper. When a certain amount of paper has accumulated on plate 7, as indicated on Fig. 2, the plate tilts downwards, owing to the increase of weight, opening valve 9 so as to operate the jet, which will then divide the paper web in two parallel strips.

The tearing of the paper will accordingly stop when reaching the division lines. Then the jet is moved in some suitable manner towards the side of the division line on which the tearing of the paper has commenced, thus re-establishing the paper web in full width. It will be understood that the actuation of the jet instead of taking place by direct connection as indicated, may also take place by the intermission of a suitable relay, for instance of the electric type.

Claim.

In a paper making machine a wire cloth, a couch cylinder, means for dividing the paper web on the wire cloth in two or more parallel strips and means actuated by the weight of torn off paper for automatically actuating said dividing means in case tearing of the paper web should be started owing to part of the paper being carried along with the wire cloth about the couch cylinder.

In testimony whereof I affix my signature.

NILS ANDOR JACOBSEN.
